(57) **CLAIM**

The ornamental design for the handle, as shown and described.

DESCRIPTION

FIG. 1 is a perspective top, rear and left side view of a handle showing the new design;

FIG. 2 is a top plan view thereof;

FIG. 3 is a bottom plan view thereof;

FIG. 4 is a right side elevation view thereof; and,

FIG. 5 is a left side elevation view thereof.

The ornamental design which is claimed is shown in solid lines in the drawings. The broken lines in the drawings are for illustrative purposes only and form no part of the claimed design.
